HANDLE FOR MEDICAL DIAGNOSTIC INSTRUMENTS

William S. Pilgrim, Port Byron, N.Y., assignor to Welch Allyn, Inc., Skaneateles Falls, N.Y.

Filed July 1, 1971, Ser. No. 159,085

Term of patent 14 years

Int. Cl. D24—02

U.S. Cl. D83—12

FIG. 1

FIG. 2

FIG. 3

FIG. 4

FIG. 5

FIG. 1 is a front elevation of a handle for medical diagnostic instruments embodying my new design;

FIG. 2 is a right side elevation thereof, the left side being a mirror image;

FIG. 3 is a rear elevation thereof;

FIG. 4 is a bottom plan view thereof; and

FIG. 5 is a top plan view thereof.

I claim:

An ornamental design for a handle for medical diagnostic instruments, substantially as shown.
